UNITED STATES PATENT OFFICE

103,345

DESIGN FOR A LACE INSERT

Albert Ruchman, New York, N. Y.

Application January 30, 1937, Serial No. 67,350

Term of patent 3½ years

To all whom it may concern:

Be it known that I, Albert Ruchman, a citizen of the United States of America, residing in Manhattan, county of New York and State of New York, have invented a new, original, and ornamental Design for a Lace Insert, of which the following is a specification, reference being had to the accompanying drawing, forming part thereof, wherein,

The figure is a plan view of a lace insert showing my new design.

I claim:

The ornamental design for a lace insert, substantially as shown.

ALBERT RUCHMAN.
